TRIGGER MECHANISM FOR GUNS.

No. 821,557.

Specification of Letters Patent.

Patented May 22, 1906.

Application filed August 22, 1904. Serial No. 221,768.

To all whom it may concern:

Be it known that I, KARL VÖLLER, engineer, a subject of the German Emperor, residing at 47 Jülicherstrasse, Düsseldorf, Germany, have invented certain new and useful Improvements in Trigger Mechanism for Guns; and I do hereby declare the following to be a full, clear, and exact description of the invention, such as will enable others skilled in the art to which it appertains to make and use the same.

My present invention relates to the trigger mechanism of guns, and more especially to that kind of such mechanisms in which the action of the same lever or trigger effects the compression or cocking of the spring actuating the firing bolt or pin and also the release of the same. The main peculiarity of this kind of trigger mechanism is this that, after firing, the mechanism automatically returns into the normal position—that is, the position in which it is ready for firing—every time it is released. In mechanisms of this kind hitherto two springs were usually employed, of which the one served the purpose of projecting the firing-pin forward against the percussion-cap in the base of the cartridge, while the other had for its object to reset the mechanism into its normal position after firing or after every partial retraction of the trigger.

My present invention consists in an improved arrangement of the parts of such mechanism by which the necessity of using this second spring is obviated, the resetting of the mechanism as well as the firing action both being operated by a single spring. More especially the invention consists in making the rest upon which the spring actuating the firing-pin bears yielding instead of rigid and in providing means for transmitting the reaction of the said spring upon such yielding rest to the trigger, which is thus reset to its normal position by the said reaction.

My invention presents the further advantages, as used in connection with the type of breech mechanism shown in the accompanying drawings, of simplicity of construction and ease of assembling and dismantling to replace or repair injured or broken parts as compared with earlier attempts to combine with the trigger-setting mechanism means for simultaneously compressing the firing-pin spring.

Of the accompanying drawings, Figures 1 to 3 are vertical sections showing my improved trigger mechanism in different positions. Fig. 4 is a detail, and Fig. 5 is a view, of the complete mechanism seen from below.

The same parts are indicated by the same letters of reference in all the figures.

B is the barrel of the gun, which is shown broken off just in front of the breech.

C is a cartridge shown in the operative position.

D is the usual wedge-shaped breech-block. The breech-block D contains a cylindrical bore f', the center line of which coincides with the center line of the main bore of the gun when the breech-block is adjusted for firing. The bore f' serves as a guide for the firing-pin f. This consists of a hollow cylinder or sleeve f² and the bolt or firing-pin proper, f³, secured to the inside of said sleeve by means of a screw-thread, as shown in the drawings, or by any other approved means. Surrounding the pin f³ and inside the sleeve f² is placed a spring g, which serves to project the pin forward when compressed and released, and thus to explode the percussion-cap placed in the usual manner in the center of the base of the cartridge-case C. The sleeve f² is provided at its lower side with a projecting shoulder e. This shoulder co-operates with a projection on the cocking-pawl d, pivotally supported by the compression-lever c. A second pawl c', likewise pivotally supported by c, co-operates with the cocking-pawl d. The trigger a is pivoted on a fixed pin b, secured in the breech-block, and is also pivotally connected to the lever c.

The operation of these parts is assumed to be understood, since the mechanism thereby constituted forms the subject-matter of my prior patent, No. 740,716. When the trigger is drawn, the lever c is swung into the position shown in Fig. 2 and the firing-pin f is cocked or retracted. By a further downward pull on the trigger the pawl c' is tripped, as shown in Fig. 3, and the firing-pin is consequently projected forward by its spring g. Thus far the herein-described mechanism is known and does not of itself form part of my present invention. These means for cocking and releasing the firing-pin are arranged in an elongated recess m, extending at substantially right angles to the bore f', containing the

firing-pin to the lower outer side of the breech-block. It will thus be seen that upon the removal of the pivot *b* the trigger *a* and the cocking and releasing mechanism can be withdrawn bodily from the recess *m* for cleaning, repair, or renewal, and as easily restored into operative relation to the firing-pin. This is fully set out and claimed in my patent referred to, and is only of importance here as making clear the problem to be solved in combining these advantageous features of construction with the compression of the firing-pin spring.

The trigger *a* is provided with a cam-surface, as at *k*, and this cam-surface bears against a corresponding surface on the lower end of a lever *h*, pivoted at *i*. The lever *h* extends upward beyond its pivot, and its upper end *h'* is placed opposite the rear end of the recess or bore *j'* in the breech-block containing the firing-pin *f*. Thus the rear end of the spring *g* instead of pressing against a stationary rest is made to bear against the upper arm *h'* of the lever *h*, and thereby the pressure of the spring is transmitted through lever *h* to the cam-surface *k* of the trigger *a*. The operation of this arrangement is as follows: When the trigger is drawn, not only is the firing-pin cocked, but the cam-surface *k* also acts upon the lower arm of the lever *h*, forcing it backward, as illustrated in Fig. 2. Since the pin *i* is fixed, the upper end of the lever *h* is forced forward, and the spring *g* is thereby compressed to a somewhat greater extent than would be the case if it bore against a stationary rest. When the pawl *c'* is tripped, the first action of the spring *g* is to project the firing-pin forward, as shown in Fig. 3, because there is no resistance to this movement. The point of the firing-pin enters the cartridge and explodes the percussion-cap. As soon as the pin has reached the forward end of its bore, however, it forms a stationary rest for the forward end of the spring *g*, and the whole force of that spring is therefore now brought to bear upon the upper end of the lever *h*. This upper arm *h'* is forced backward and the lower arm correspondingly forward, and the latter, by means of the cam-surface coöperating with the cam-surface *k* on the trigger *a*, resets the latter. The trigger in being reset simultaneously acts to reset the other parts, so that now the whole mechanism is again in its initial position. (Illustrated in Fig. 1.)

The preferred shape of the lever *h* will be seen in Fig. 4, in which it is separately illustrated, and Fig. 5 shows the respective positions of the parts as seen from below. I wish it, however, to be understood that my invention is not strictly confined to the special means and shapes of parts illustrated, since any expert will be able to substitute various modifications without altering the nature of my invention.

As combined with the particular form of cocking and releasing mechanism illustrated in the drawings, however, the invention presents the advantages that by arranging the lever *h'* as a straight lever in a straight channel or recess alongside and parallel to the recess containing the cocking and releasing mechanism, mounting the trigger and its mechanism on the single removable pivot *b*, and mounting the lever *h'* on its pivot *i* there is obtained a peculiarly compact and simple firing mechanism which is correspondingly efficient and reliable in operation, not liable to disarrangement, and one remarkably easy to dismantle and to reassemble. If, for instance, it is desired to remove the firing-pin for cleaning or to renew a broken spring *g* or point *f'*, the lever *h'* is pressed forward, compressing the spring, its pivot unseated, and it is withdrawn downward, when the firing-pin, sleeve, spring, &c., are free to be taken out to the rear, as will be seen from Fig. 1. When the pivot *b* is removed, the trigger *a* and the cocking and releasing mechanism may also be withdrawn. Thus by the removal of two pivots all of the movable parts of the breech-block which pertain to the firing are removed and made accessible and are as easily replaced by a reversal of the operation.

By arranging the firing-spring *g* to bear directly upon the end of the lever *h'* a multiplicity of parts is avoided, and a larger spring and pin can be used than could otherwise be the case without enlarging the cavity, and thus weakening the breech-block.

It has been a disadvantage common to previous attempts to combine a spring-compressing mechanism with known forms of trigger mechanism that the result was a complicated mechanism, liable to disarrangement, difficult to dismantle and to reassemble, and occupying too large a portion of the breech-block, with a consequent weakening. This I have avoided by the peculiarities of constructions shown.

Having now particularly described and ascertained the nature of my said invention and in what manner the same is to be performed, I declare that what I claim is—

1. In trigger mechanism for guns, the combination, with a firing-pin, a coiled spring operating in the direction of its axis only and serving to project said pin forward, a trigger, and means for cocking and releasing the firing-pin when the trigger is drawn, of a lever serving as a rear abutment for the spring and adapted to transmit the force of the spring to the trigger and thereby to reset the same to its normal position.

2. In trigger mechanism for guns, the combination, with a firing-pin, a spring adapted to project the pin forward, a trigger, and means for cocking and releasing the said firing-pin when the trigger is drawn, of a lever inserted directly between the rear end of

the said spring, and a cam-surface on said trigger.

3. In trigger mechanism for guns, the combination, with a firing-pin, a coiled spring operating in the direction of its axis only and serving to project said pin forward, a trigger, and means for cocking and releasing said firing-pin when said trigger is drawn, of a lever having two arms and a fixed pivot, one arm 10 of said lever bearing directly against the rear end of said spring and the other arm of said lever bearing against a cam-surface on said trigger, the whole mounted in a breech-block having an opening to the rear in line with the 15 spring.

4. In trigger mechanism for guns, the combination, with a firing-pin, a spring for projecting said pin, a trigger rocking on a fixed pivot and provided with a cam-surface, 20 means for cocking and releasing said firing-pin when said trigger is drawn, of a substantially straight lever rocking on another fixed pivot alongside the cocking and releasing mechanism and having two arms one of which 25 is provided with a cam-surface adapted to co-operate with the cam-surface on the trigger and the other of which bears directly against the rear end of the said spring.

5. In a trigger mechanism for guns, the

combination, with a firing-pin, a spring arranged to project said pin forward, a trigger, and means arranged in a substantially straight recess for cocking and releasing the firing-pin when the trigger is drawn, of a substantially straight lever arranged in a recess 35 parallel to the first recess, one arm of said lever serving as a rear abutment for the spring and the other arm bearing against the trigger.

6. In a trigger mechanism for guns, the 40 combination, with a firing-pin, a spring arranged to project said pin forward, a trigger, and means arranged in a substantially straight recess extending transversely of the firing-pin for cocking and releasing the pin 45 when the trigger is drawn, of a substantially straight lever arranged in a recess also transverse to the firing-pin, one arm of the lever bearing directly against the rear end of the spring and the other arm of the lever having 50 a cam engagement with the trigger.

In testimony whereof I have affixed my signature to this specification in the presence of two witnesses.

KARL VÖLLER.
